UNITED STATES PATENT OFFICE.

WILLIAM A. RINGLER, OF PHILADELPHIA, PENNSYLVANIA, ASSIGNOR TO THE GLOBE-WERNICKE CO., A CORPORATION OF OHIO.

VISIBLE-INDEX-CARD CARRIER.

Application filed January 2, 1923. Serial No. 610,166.

To all whom it may concern:

Be it known that I, WILLIAM A. RINGLER, a citizen of the United States, residing at Philadelphia, in the county of Philadelphia and State of Pennsylvania, have invented certain new and useful Improvements in Visible-Index-Card Carriers, of which the following is a full, clear, and exact description.

This invention relates to card index devices of the so-called visible index type in which a series of index cards are supported for sliding movement in a frame, with the free edges of the cards projecting one beyond the other when the cards are together so as to leave a narrow portion of a surface of each card exposed along its free edge, which portion is adapted to carry suitable card identification characters or information in a position to be always visible. It particularly relates to an index card support for such devices and is in the nature of an improvement upon the types of card supports shown and claimed broadly in my copending application Serial No. 542,573, filed March 10, 1922. An object of the invention is to provide an improved index card support for such index devices which will enable the rapid attachment of a card thereto or the withdrawal of a card therefrom; which will mount the card to swing freely in a manner to expose either face thereof for the purpose of obtaining information therefrom or the entry of information thereon; which may be formed of stock and sheet material in a practical manner by a minimum number of simple cutting and bending operations; and which is simple, thin, light in weight, compact, convenient, durable and inexpensive. Other objects and advantages will be apparent from the following description of an embodiment of the invention and the novel features will be hereinafter particularly pointed out in claims.

In the accompanying drawing:

Fig. 1 is a plan of an index device having card supports constructed in accordance with the invention;

Fig. 2 is a perspective of one of the improved card supports;

Fig. 3 is a transverse section through the same taken substantially along the line 3-3 of Figure 1;

Fig. 4 is a plan of the blank from which one part of the support is formed; and

Fig. 5 is a plan of the blank from which another part of the support is formed.

In the illustrated embodiment of the invention a frame 1 which may be formed of any suitable material, such as sheet metal, is provided on opposite sides with inturned peripheral flanges 2 which extend parallel with the same face of the frame so as to provide with the face of the frame, internal oppositely-facing longitudinally extending grooves. These grooves along opposite sides of the frame are utilized as guideways for supporting the card-supports 3 for bodily sliding movement along the frame, one of the supports being shown separately in Figure 2. An elongated, flat strip 4 of sheet metal has its ends 5 rolled backwardly thereon, upon the same face of the strip, so as to form enlarged ends which serve as bearings when the support slides in the guideways of the frame with the flat face of the strip parallel with the face of the frame. The card-supports normally abut against one another, edge to edge, and the enlarged terminals at the ends prevent one carrier from overlapping the other when the frame is tilted or carried about. A wire 6 is disposed upon one face of the strip 4, along an edge thereof, and integral tongues 7 extending from the edge of the strip 4 along which the wire is disposed are rolled, turned, or otherwise formed around the wire so as to effectively secure it to the face of the strip. The corners of the inturned ends of the strip are notched, as at 8, so as to allow the ends of the wire to extend into and be concealed within the rolled or enlarged ends of the strip 4.

An elongated strip 9 of sheet metal has its opposite edges turned back thereon toward one another on the same face of the strip, and disposed in spaced relation to the face of the strip. These turned edges form flanges 10 and 11 which provide, with the face of the strip, oppositely disposed grooves that extend lengthwise of the strip. One

of the flanges, such as 11, is spaced from the face of the strip a greater amount than the other flange and preferably overlaps the other strip in slightly spaced relation thereto. The strip 9 is disposed lengthwise of the strip 4 with the outer surface of one of the flanges extending along and in close proximity to the intermediate portion of the wire 6. Tongues 12, which are integral 10 with the strip 9, extend from the edge thereof that abuts the wire 6, and are turned, rolled or otherwise formed around the wire 6 so as to provide an articulated connection between the wire and the strip 9 enabling 15 the strip 9 to be swung about the wire 6 as a hinge. The strip 9 may be hereinafter referred to as a card-carrier.

An edge portion 13 of an index card 14 is doubled back upon itself to form an offset or angular edge portion which is adapted to be inserted between the grooves of the carrier 9 and anchor the index card therein. One groove of each carrier, such as that formed by the flange 11, has a greater width between the side walls of the groove than the corresponding width of the opposite groove of the same strip or carrier, and the flange 11 forming this groove overlaps with the other flange in spaced relation therewith. The free edge of the angular edge 13 of the index card is inserted into the groove having the narrower width and the doubled back edge of the card is inserted into the groove having the greater width, as shown in Figure 3. The body of the index card extends through the space between the overlapping flanges. With this arrangement the cards may lie substantially flat over the flange 10. One of the flanges, such as 10, which forms one of the grooves, is extended nearer an end of the carrier than the other flange which forms the opposite groove of the same carrier so as to facilitate the insertion therein of the offset or angular end of the index card.

A holding member 15 is provided with extensions 16 which project into the guideways in which the card-supports slide, so as to secure the holding member to the frame with provision for adjustment along the same in the direction of adjustment of the card supports. A strip 17 of suitable flexible material, such as fabric or spring steel, preferably the latter, is anchored at its ends to the ends of the frame and extends lengthwise along the face of the frame beneath the card-supports. The strip passes through parallel apertures 18 in the holding member 15, preferably entering and leaving the member from the under face thereof so that as the member is adjusted along the frame, it will be frictionally held in any adjusted position. The holding member is shifted along the guideways to

hold the card-supports together and against one end of the frame, and is adjustable for the purpose of allowing the insertion of additional card-supports between the guideways or for crowding the remaining card supports together after some have been removed from the frame.

The cards may be easily and rapidly attached to the card-supports by sliding the bent-over edge portions endwise into the grooves formed by the flanges 10 and 11 and the cards, when so attached, will be effectively secured to the supports. They may be swung with the carrier 9 about the wire 6 as a pivot pin so as to expose either face for inspection or entry of information thereon, the cards at the right in Figure 1 being in position to expose one face of the cards and the card at the left in Figure 1 being in the position in which its rear or under face is exposed. The wire 6 is standard stock material, and the strips 4 and 9 can be stamped to the desired size and shape from ordinary sheet metal, and formed by dies into the desired shape and in the desired assembly, in a manner well known in the sheet metal working art. The card support, when complete, is thin so that an index device utilizing them may be made very thin. The support is also light in weight, durable, and because of its manufacture by stamping and die-forming methods, the cost of manufacture is relatively small.

It will be obvious that various changes in the details and arrangements of parts herein described and illustrated for the purpose of explaining the nature of the invention, may be made by those skilled in the art within the principle and scope of the invention, as expressed in the appended claims.

I claim:

1. In a visible index device, a member adapted to extend between and slide in spaced parallel guides, a wire secured to the member, a sheet metal hinge element having a portion thereof bent around the wire to provide a pivotal connection to the member and another portion bent upon itself to engage with and detachably hold an index card.

2. In a visible index device, an element adapted to extend between and slide in spaced parallel guides, a sheet metal hinge element having a portion thereof bent around a portion of the sliding element to form a pivotal connection between the elements, said hinge element having means to detachably hold an index card for movement therewith about the pivotal connection so as to expose to view either face of the card.

3. In a visible index device, an element

- adapted to extend between and slide in spaced parallel guides, a sheet metal hinge element having a portion thereof along an edge formed around a portion of the sliding element to form a pivotal connection between the elements, said hinge element having other portions bent thereon to form flanges extending toward one another and lengthwise of the element to form index card attaching means.
4. In a visible index device, an element adapted to extend between the slide in spaced parallel guides, a sheet metal hinge element having a portion thereof along an edge bent around a portion of the sliding element to form a pivotal connection between the elements, said hinge element having other portions bent thereon to form flanges extending toward one another in different planes to form opposing guides between which may be supported an index card with a bent-over edge by sliding the bent-over edge endwise between the flanges.
5. In a visible index device, an element adapted to extend between and slide in spaced parallel guides, a sheet metal hinge element having a portion thereof along an edge bent around a portion of the sliding element to form a pivotal connection between the elements, said hinge element having other portions bent thereon to form flanges extending toward one another in different planes and overlapping for slidably receiving the bent-over edge of an index card which is inserted between the grooves endwise of the bent-over edge.
6. In a visible index device, an element adapted to extend between and slide in spaced parallel guides, a sheet metal hinge element having opposite longitudinal edges bent thereon toward one another on the same face of the element to form opposing guide grooves in which a bent-over edge of an index card may be removably secured, said hinge element also having a tongue extending from an edge thereof beyond the flanges and formed around a portion of the sliding element to form a hinge connection between the elements.
7. In a visible index device, an elongated strip of sheet metal adapted to extend between and slide in spaced parallel guides, a wire extending along the upper face and adjacent one edge thereof, the strip having tongues extending from the said one edge and bent around the wire to anchor it thereto, and a hinge element pivotally mounted on the wire and adapted to removably support an index card.
8. In a visible index device, an elongated strip of sheet metal adapted to extend between and slide in spaced parallel guides, a wire extending along the upper face and adjacent one edge thereof, the strip having tongues extending from the said one edge and bent around the wire to anchor it thereto, a hinge element of sheet metal having a tongue extending from an edge thereof and bent around the wire to form a hinged connection thereto, said hinge element also having portions bent thereon to removably support an index card.
9. In a visible index device, an elongated flat strip of sheet metal having its ends rolled over to form bearing ends, a wire extending along the face of the strip and into the rolled ends, tongues on the strip bent around the wire to secure it thereto, and a hinge element pivotally mounted on the wire and adapted to removably support an index card.
10. In a visible index device, an elongated flat strip of sheet metal having its ends rolled over to form bearing ends, a wire extending along the face of the strip and into the rolled ends, tongues on the strip bent around the wire to secure it thereto, a hinge element of sheet metal having a tongue extending from an edge thereof and bent around the wire to form a hinged connection thereto, said hinge element also having portions bent thereon to removably support an index card.
11. In a visible index device, an elongated flat strip of sheet metal having its ends rolled over to form bearing ends, a wire extending along the face of the strip and into the rolled ends, tongues on the strip bent around the wire to secure it thereto, a flat sheet-metal hinge element having its lengthwise edges doubled over toward one another on the same face to form opposing grooves in which a bent-over edge of an index card may be removably supported by sliding the bent edge endwise into the opposed grooves, and a tongue integral with the hinge element, extending from a lengthwise edge thereof beyond the bent-over portion of the edge, and turned around the wire to form an articulated connection thereto.
12. In a visible index device, a sliding index card support comprising an elongated flat strip of sheet metal having its ends rolled over to form bearing ends, a wire disposed along a face of the strip at one edge, the rolled ends of the strip each having a notch therein for receiving an end of the wire, tongues extending from the edge of the strip along which the wire extends, and turned around the wire to anchor it to the strip, an elongated card carrier of sheet metal having its opposite edges turned toward one another on the same face of the strip to form opposed guide grooves, said grooves being adapted to receive and support an offset edge portion of an index card which is slid endwise between the grooves, said carrier being disposed with the outer

surface of one of its edges extending along the wire, and a tongue extending from said one of the edges of the carrier, and turned around the wire to form an articulated connection therewith, whereby a card attached to the carrier may be swung with the carrier about the wire as a pivot to expose

either face for inspection or entry of information thereon, and be shifted bodily with the flat strip.

10
